SUPPORT FOR PICTURES OR THE LIKE

Filed Aug. 18, 1922

UNITED STATES PATENT OFFICE.

WLADISLAUS BRIZGIS, OF TURNERS FALLS, MASSACHUSETTS.

SUPPORT FOR PICTURES OR THE LIKE.

Application filed August 18, 1922. Serial No. 582,646.

To all whom it may concern:

Be it known that I, WLADISLAUS BRIZGIS, a citizen of Lithuania, residing at Turners Falls, in the county of Franklin and State 5 of Massachusetts, have invented certain new and useful Improvements in Supports for Pictures or the like, of which the following is a specification.

This invention relates to frames for pictures, photographs, mirrors or the like, having more particular reference to frames provided with supporting members which hold them in an approximately upright position.

The invention has for an object to provide 15 a novel frame of this type having an adjustable foot adapted to engage different angled surfaces.

For further comprehension of the invention, and of the objects and advantages 20 thereof, reference will be had to the following description and accompanying drawings, and to the appended claims in which the various novel features of the invention are more particularly set forth.

25 Fig. 1 of the drawings is a perspective view of a picture frame constructed according to my invention.

Fig. 2 is a side view, with parts in vertical section, showing a slightly changed construction.

30 Fig. 3 is a side view of the frame shown in Fig. 2, but adjusted to a different position.

In the form of the invention shown in Fig. 1 of the drawings the reference numeral 10 35 indicates a rectangular frame in which is placed a picture 11. The details of construction whereby the frame engages the picture are not shown as the same have no reference to the present invention.

40 Fixed on the top of the frame is a socket 12 in which is received a ball 13 on the end of a bent rod 14 forming the upper end of a strut whose lower end is formed by a hollow bar 15 into which the rod telescopically projects, being secured in selected positions by a set screw 16.

The lower end of the strut 14, 15 is pivotally connected as at 18 with an approximately horizontal arm 19 having a cross piece 20 at one end which acts as a support for the lower end of the frame, the back of the latter resting freely against the cross piece. The other end of the arm is in the form of a wood screw 21 which may be 55 screwed into any desired surface to support

the frame, a disk-flange 22 at the base of the screw limiting the movement thereof.

In the embodiment of the invention shown in Figs. 2 and 3 the frame 10' and strut comprising rod 14' and hollow bar 15' are the 60 same as shown in Fig. 1. In this construction however, instead of the one-piece bracket arm 19 I provide an arm composed of two members 25 and 26 the former having a cross-piece 27 at one end, and the latter 65 a wood screw 28 at its opposite end. These members overlap one another at their adjacent ends, which are longitudinally slotted as at 29, and are secured together, and to the lower end of the hollow bar 15' by a nut 30 70 threaded on a screw 31, this screw passing through a suitable aperture in the bar 15' and through the slots 29.

Adjacent the wood screw 28 the member 26 is provided with a machine screw threaded portion 33 of larger diameter than the wood screw and over this portion is screwed a sleeve 34 having a disk flange 35 at one end. When the frame is mounted on a vertical or inclined surface such as that indicated by the line 36 in Fig. 2, the flange 35 is tightened against said surface after the wood screw 28 has been entered thereinto.

By reason of the telescopic construction of 85 the strut, and the adjustable two part construction of the supporting arm, the frame 10' may be mounted at substantially any desired angle.

If it is so desired the frame may be adjusted to rest freely on a horizontal surface, as indicated in Fig. 3, the member 26 being adjusted to a vertical position, while the sleeve 34 is screwed downwardly until the wood screw 28 is covered, the flange 35 forming 90 the foot of the support.

Having thus described my invention what I claim as new and desire to protect by Letters Patent of the United States is as follows:

1. In combination, a frame, a strut secured to the upper portion of said frame by a universal joint, said strut consisting of two parts having telescopic connection with one another, an arm to which said strut is attached at its lower end, said arm having a wood screw at one end adapted to be secured in a fixed supporting element and a cross piece at the other adapted to have the lower part of the frame rest thereagainst.

2. In combination, a frame, a strut secured to the upper portion of said frame by a universal joint, said strut consisting of two parts having telescopic connection with one another, an arm to which said strut is attached at its lower end, said arm having a wood screw at one end adapted to be secured in a fixed supporting element and a cross piece at the other adapted to have the lower part of the frame rest thereagainst, said arm comprising two members having hinge connection with one another.

3. In combination, a frame, a strut secured to the upper portion of said frame by a universal joint, said strut consisting of two parts having telescopic connection with one another, an arm to which said strut is attached at its lower end, said arm having a wood screw at one end adapted to be secured in a fixed supporting element and a cross piece at the other adapted to have the lower part of the frame rest thereagainst, said arm comprising two members having hinge connection with one another, and a sleeve adjustable along said arm to cover said screw, for the purpose specified.

4. In combination, a frame a strut secured to the upper portion of said frame by a universal joint, said strut consisting of two parts having telescopic connection with one another, an arm to which said strut is attached at its lower end, said arm having a wood screw at one end adapted to be secured in a fixed supporting element and a cross piece at the other adapted to have the lower part of the frame rest thereagainst, said arm

comprising two members having hinge connection with one another, and a sleeve threaded on said arm to be adjustable therewith, and cover said screw at certain times, 40 said sleeve having a flange at one end, for the purpose specified.

5. In combination, a frame, a strut pivotally connected to the upper end of said frame, a supporting arm for said frame 45 adapted to engage the lower part thereof and comprising two sections having longitudinally slotted overlapping ends, fastening means passing through said slotted ends and the lower end of said strut, a wood screw 50 on the other end of one of said members, adapted to engage in a fixed support and a foot adjustable along said member to cover said wood screw.

6. In combination, a frame, a strut pivotally connected to the upper end of said frame, a supporting arm for said frame adapted to engage the lower part thereof and comprising two sections having longitudinally slotted overlapping ends, fastening 60 means passing through said slotted ends and the lower end of said strut, a wood screw on the other end of one of said members, adapted to engage in a fixed support and a foot adjustable along said member 65 to cover said wood screw, said foot comprising a flanged sleeve threaded on said member.

In testimony whereof I have affixed my signature.

WLADISLAUS BRIZGIS.
